UNITED STATES PATENT OFFICE

2,073,121

LIQUEFIER SYSTEM FOR SOLIDIFIED
CARBON DIOXIDE

Frank C. Seck, Oklahoma City, Okla.

Application August 13, 1934, Serial No. 739,630

11 Claims. (Cl. 62—91.5)

This invention relates to liquefier systems for solidified carbon dioxide wherein is embodied such structural features as are shown and described in my co-pending application for United States Letters Patent Serial Number 719,740, filed April 9, 1934, and in my United States Letters Patent No. 1,928,396, issued September 26, 1933.

One of the important objects of this invention is to provide a liquefier system that is cheap to manufacture, is strong and durable, will permit of adjustment both during the initial assembly and while servicing and presents an exceptionally compact liquefier system having novelly related tanks forming the main reservoir and reserve containers.

It has been found in practice that the proper combination between the component tanks of a liquefier system is difficult to establish and maintain where one tank is supported by the other. This invention, therefore, provides structure that is commercially practical in this regard and one exemplification of the invention is illustrated in the accompanying drawing, wherein:

Figure 1 is a side elevation of a liquefier system made in accordance with this invention.

Fig. 2 is an edge elevation of the same.

Fig. 3 is a top plan view, and,

Fig. 4 is a horizontal cross section taken along line IV—IV of Fig. 2.

In constructing the main reservoir, the same should be made to embody the features described in my aforementioned co-pending application, wherein is disclosed the proper means for inserting solidified carbon dioxide into main reservoir 6. This reservoir is preferably cylindrical and should rest upon a number of supporting legs 8, whereby the bottom of the reservoir 6 is elevated from the floor or other supporting surface. The top of reservoir 6 is provided with a closure 10 which is locked in place by a cross bar 12 so that reservoir 6 is gas tight, with the exception of the hereinafter mentioned connections which draw off the carbon dioxide gas after it has been formed by the sublimation of the solid within reservoir 6.

It is oftentimes desirable to have a reserve supply of carbon dioxide gas available so that in the event main reservoir 6 is entirely emptied, there will be enough gas to carry on commercial operations until a new supply of gas can be built up in main reservoir 6. Accordingly, a reserve tank 14 is provided in this system, which is preferably supported by main reservoir 6 in unique manner and in juxtaposition thereto as shown in the drawing. Special connections between main reservoir 6 and reserve tank 14 allow filling of this tank and then closing it off from the system while carbon dioxide is being drawn directly from reservoir 6.

In the example illustrated, pipe 16 is in connec-

tion with the upper part of reservoir 6 and extends laterally therefrom to join vertical pipe 18 through the medium of valve 20. This valve 20 may have a blow-out plug 22 to relieve dangerously excessive pressures that might be built up within the system. A second valve 24 is located in pipe 18 and may be used to close off tank 14 from the remaining part of the system. The pipe 26 extends from pipe 18 between valves 20 and 24 and is joined to any suitable work not here shown. A separate valve 28 within pipe 26 affords an independent means of opening and closing pipe 26. Obviously, when it is desired to pass gas into tank 14, valves 20 and 24 are opened and valve 28 closed. When tank 14 has been filled, valve 24 will be closed, thereby to retain a reserve supply in tank 14 and valves 20 and 28 opened so that the gas will flow directly from the main reservoir 6 through pipes 16 and 26 to the work.

When constructing such a liquefier system, tank 14 should be appreciably smaller than main reservoir 6 and pipes and valves just mentioned should be located as shown in Figs. 1, 2 and 3. In so positioning these connections they will assist in holding reserve tank 14 against reservoir 6 and the connection to tank 14 is preferably through the top.

It has been found in constructing this simple liquefier system that tank 14 is hard to position without creating a strain on the connections through which the gas will pass. As a matter of fact, if the connections are not properly made and a strain is exerted, a leak will occur after the system is put in use. An important improvement, therefore, which this invention contemplates is found in the means for adjustably supporting tank 14. This means is in the form of a bracket 30 which is secured to the bottom of reservoir 6 and extends laterally therefrom to a point beneath tank 14. This bracket 30 has an opening 32 formed therethrough to receive a screw-threaded stem 34 integral with and depending from the bottom of tank 14. There is a nut 36 both above and below bracket 30 respectively in screw-threaded engagement with stem 34 which permits longitudinal adjustment of tank 14 relative to reservoir 6. After or during the placement of the connections at the top of the two tanks, nuts 36 are tightened so as to hold tank 14 in a predetermined set position. Legs 8 are high enough to permit stem 34 to project downwardly as shown, and the system, including the two tanks 6 and 14 will be, thereby, rigidly assembled without special equipment or tools. The entire system is in the form of a unit that may be moved about with ease and in case of adjustment that might become necessary with regard to any pipe or valve, the same can be made without endangering the relation between the remaining parts of the liquefier system.

It is understood that the specific embodiment of the points of this invention might be different from that exemplified and illustrated in the accompanying drawing.

- 5 Having thus described the invention, what is claimed as new and desired to be secured by Letters Patent is:
1. A liquefier comprising a main reservoir; a reserve tank supported by the main reservoir in side-by-side relation; pipes joining the upper ends of said reservoir and tank; and means for maintaining the reserve tank at a predetermined adjusted position longitudinally of the main reservoir.
  - 15 2. A liquefier comprising a main reservoir; a reserve tank in juxtaposition with said main reservoir and appreciably shorter than the same; a pipe interconnecting the upper portion said reservoir and upper portion of the tank having a pair of manually operable valves interposed therein; and a take-off tube in connection with the pipe between said valves, all parts of said liquefier being supported by the main reservoir to create a liquefier system movable as a unit.
  - 25 3. A liquefier comprising a main reservoir adapted to contain solidified carbon dioxide and the carbon dioxide gas resulting from its sublimation; a reserve tank appreciably smaller than the main reservoir in juxtaposition with and supported by the latter; a pipe interconnecting said reservoir and tank having a valve therein to control the flow of said gas therethrough; and means for maintaining the said reserve tank at a predetermined adjusted position longitudinally of the said main reservoir.
  - 40 4. A liquefier comprising a main reservoir adapted to contain solidified carbon dioxide and the carbon dioxide gas resulting from its sublimation; a reserve tank appreciably smaller than the main reservoir and supported by the latter; pipes interconnecting said reservoir and tank having control valves therein, said tanks having their longitudinal axes in parallel relation; and means for adjustably supporting the reserve tank in predetermined adjusted positions along its axial line.
  - 45 5. A liquefier comprising a main reservoir adapted to contain solidified carbon dioxide and the carbon dioxide gas resulting from its sublimation; a reserve tank appreciably smaller than the main reservoir and supported by the latter; pipes interconnecting said reservoir and tank having control valves therein, said tanks having their longitudinal axes in parallel relation; and means for adjustably supporting the reserve tank in predetermined adjusted positions along its axial line, said pipes serving to preclude movement of the top of the auxiliary tank from said main reservoir.
  - 50 6. A liquefier comprising a main reservoir adapted to contain solidified carbon dioxide and the carbon dioxide gas resulting from its sublimation; a reserve tank appreciably smaller than the main reservoir and supported by the latter; pipes interconnecting the upper portions of said tanks to permit the flow of gas from one to the other; and adjustable means for establishing a supporting relation between the tanks comprising a threaded stem depending from the lower end 65 of the reserve tank, a laterally projecting bracket rigid with the lower end of the main reservoir and having an opening formed therein to re-

ceive the said stem, and a nut in screwthreaded engagement with the said stem above and below the bracket respectively.

7. A liquefier comprising a main reservoir adapted to contain solidified carbon dioxide and the carbon dioxide gas resulting from its sublimation; a reserve tank appreciably shorter than the main reservoir and disposed in juxtaposition to the main reservoir intermediate its ends; pipes and control valves establishing connection between the main reservoir and reserve tank extending laterally from the former near the upper end thereof and intermediate the said upper end and the upper end of the reserve tank and joining the reserve tank on the longitudinal axis thereof at its top; and means adjustably supporting the said reserve tank at the bottom thereof permitting longitudinal adjustment of the reserve tank as the said pipes and control valves require adjustment.

8. A liquefier of the character described comprising a main reservoir; a reserve tank against the side of the main reservoir; pipes and valves joining the top of said reserve tank and the side of said main reservoir whereby to allow the passage of gas from reservoir to tank; and adjustable means interconnecting the main reservoir and tank to support the reserve tank in predetermined positions along the side of the main reservoir as the manipulation of the pipes and valves increases or decreases their length.

9. A liquefier of the character described comprising a main reservoir; a reserve tank against the side of the main reservoir; pipes and valves joining the top of said reserve tank and the side of said main reservoir whereby to allow the passage of gas from reservoir to tank; and adjustable means interconnecting the main reservoir and tank to support the reserve tank in predetermined positions along the side of the main reservoir as the manipulation of the pipes and valves increases or decreases their length, said adjustable means and the said pipes and valves precluding movement of the said reserve tank from the main reservoir.

10. A liquefier of the character described comprising a main reservoir; a reserve tank in juxtaposition to the main reservoir; legs to support the bottom of the main reservoir spaced from the floor; a perforated bracket extending laterally from the bottom of the main reservoir beneath the reserve tank; a screwthreaded stem rigid to the bottom of the reserve tank and extending through the perforation in the bracket; a nut in screwthreaded engagement with the said stem above and below the bracket respectively whereby to adjustably secure the reserve tank in predetermined positions; and pipes interconnecting the upper ends of the reservoir and tank.

11. A unitary liquefier system for solidified carbon dioxide comprising a main reservoir serving as a support for the remaining parts of the system; a reserve tank immediately adjacent to the main reservoir and appreciably shorter than the same; a pipe extending laterally from the side of the main reservoir between the top thereof and the top of the said reserve tank and having connection with the latter through its top; and a take-off tube in connection with said pipe.
